[57] CLAIM

The ornamental design for a garden rake, as shown or described.

DESCRIPTION

FIG. 1 is a perspective view from above of a garden rake showing our new design;

FIG. 2 is a similar perspective view thereof with the handgrip separated from the shank of the utensil;

FIG. 3 is a side elevational view thereof;

FIG. 4 is a top plan view thereof;

FIG. 5 is a front end elevational view thereof;

FIG. 6 is a rear end elevational view thereof; and

FIG. 7 is a bottom plan view thereof.

FIG. 1
